CARD SORTING DEVICE

Albert A. Rembold, San Francisco, Calif.

Application November 5, 1948, Serial No. 58,495

9 Claims. (Cl. 129—16.1)

1

This invention relates to a card sorting device for use in the selective sorting of marginally punched and slotted cards such, for example, as are shown in my United States Letters Patent No. 2,198,127 of April 23, 1940.

Cards of generally the type shown in the above patent are normally arranged in a row with the marginal openings in registration. The openings in the cards are coded and certain openings in certain cards are slotted out. By using combination of sorting needles or pins thrust through combinations of aligned openings in a row of cards, some of the cards will be retained on the needles when the latter are raised, and will be suspended from said needles while one or more may be released to drop from the cards of the row. Those that are released are the ones in which the openings in one or more of the cards are slotted out to the edge of the card in the particular combination of needles that is employed.

Heretofore attempts have been made to facilitate the sorting of the cards by providing a handle having a plate or supporting member at one end to which one of the ends of the needles of a row are removably secured. The said member is so arranged that the needles may be so spaced in the row as to provide the desired relationship for sorting out the desired card or cards. However, the cards in a stack or row are usually relatively heavy and the needles tend to sag and become distorted with the weight of the cards. Also, difficulty is encountered in maintaining the free ends of the needles in the correct spaced relationship for entering the proper holes in the cards. Furthermore, there is no means on the sorting devices for quickly and clearly determining exactly the precise combination that the arrangement of needles represents.

One of the objects of the present invention is the provision of a card sorting device that overcomes the above objections.

Another object of the invention is the provision of a card sorting device that is strong, easily and accurately manipulated, and one in which the free ends of the sorting needles are adapted to be accurately held in the correct spaced relationship during their movement through the aligned openings in a row or stack of cards irrespective of any tendency for the free ends to spring to incorrect spaced relationship.

An additional object of the invention is the provision of a card sorting device having the needles supported in a row below a lifting handle with one of the ends of the needles being free for insertion through the openings in the cards.

2

A still further object of the invention is the provision of guide means on a card sorting device to facilitate the insertion of the proper needles in the proper openings in a stack of cards.

5 An added object is the provision of a code on a card sorting device that is provided with means visibly identifying the needles with the coded card openings thus reducing the chance for error in the use of the device, and which means also facilitates the changing of the positions of the needles for new combinations.

Other objects and advantages will appear in the description and in the drawings.

15 In the drawings, Fig. 1 is an isometric view of the card sorting device including cards positioned for sorting by use of the device.

Fig. 2 is a reduced size end elevational view of the sorting device of Fig. 1 in operation over a conventional sorting tray.

20 Fig. 3 is an enlarged fragmentary part elevational and part sectional view showing the end of one of the sorting needles in a position for insertion into the holder therefor.

25 Fig. 4 is a fragmentary part sectional and part elevational view of the sliding guide and support for the needles of the sorting device, the guide itself being indicated in top plan view.

30 Fig. 5 is a cross sectional view taken along the line 5—5 of Fig. 4.

In detail, the sorting device of this invention 35 comprises a support for the needles in the form of a body member 1 that is a horizontally elongated boxlike piece having vertically disposed, opposed, horizontally elongated front and rear side walls 2, 3, opposed end walls 4, a top wall 5 and a bottom wall 6. The rear side wall extends upwardly from the bottom wall 6 only part of the distance to the top wall thus leaving a horizontally elongated gap or space 7 between the horizontally extending upper edge of rear wall 3 and the top wall 5.

40 A horizontally elongated handle 10 is secured at one of its ends to top wall 5 at a point centrally between the ends of the latter and projects at right angles to said support 1 in direction away from rear wall 3.

45 The end of handle 10 that is remote from the support 1 is secured to a strip 11 at a point centrally between the ends of the latter. Strip 11 is parallel with body 1 and at right angles to handle 10.

50 Said strip 11 is provided with a pair of depending legs 12 respectively secured at their upper ends to strip 11 at points adjacent the ends of said strip. These legs 12 are correspondingly inclined in direction away from body 1 from their

upper ends and the lower ends of said legs are respectively secured to one of the ends of a pair of corresponding parallel bars 13. The opposite ends of bars 13 are secured to the front wall 2 of support 1.

Slidable on bars 13 is a transverse, horizontal, elongated spacer element 15 for the needles that is in the form of an inverted elongated channel member having a rear side 16, top 17 and a front side 18. The front side 18 is preferably of substantially less width than the rear side 16.

The bars 13 extend through aligned openings in the sides 16, 18 of said channel member, the latter being slidable on said bars 13 from substantially end to end thereof.

The top side 17 of the channel member or spacer element 15, rotatably supports a pair of pulley wheels 19, 20 adjacent its under side and between sides 16, 18. These pulleys are adjacent the ends of the spacer element.

Cords 21, 22 are respectively secured at one of their ends to the front wall 2 of support 1 adjacent opposite ends thereof. Cord 21 extends from said support parallel with the bar 13 adjacent thereto through an opening in the rear side 16 of spacer element 15, then around a side of pulley 19 and longitudinally of the spacer 15 to pulley 20, then around a side of pulley 20 and through an opening in front side 18 to the leg 12 nearest thereto, which leg is at the side of the device opposite the pulley 19.

The other cord 22 extends from support 1 parallel with the bar 13 that is at the side of the device, opposite the side from which cord 21 extends from the support. Cord 22 extends through an opening in the side 16 and around a side of pulley 20, then longitudinally of the spacer 15 to pulley 19 and around a side of the latter and through an opening in front wall 18 of the spacer, and then to the leg 12 that is nearest thereto and to which the cord is attached.

The pulleys are each formed with a pair of outwardly opening annular grooves in their recesses that keep the cords 21, 22 from rubbing against each other where they cross at a point centrally between the ends of the spacer (Figs. 4, 5).

By the above structure the spacer 15 will be frictionally held stationary at any point in its movement along bars 13, and will be retained parallel with the support 1 and strip 11 irrespective of the point along the spacer at which force may be applied for moving the spacer along bars 13.

End pieces 23 may be secured to the ends of the spacer 15, which pieces project oppositely outwardly from said ends for manual grasping of either piece to facilitate manually moving the spacer along bars 13.

The front and rear sides of the support 1 and the rear side of the spacer 15 are formed with corresponding axially registering annular openings arranged in a horizontally extending row or rows, as shown in the cards in my aforesaid patent. These openings correspond with the marginal openings in marginally punched cards. If the openings are in staggered relationship on the cards, a corresponding arrangement of openings is in each of the side walls 2, 3, 16, of the support 1 and spacer 15. The openings in the rear wall 3 of support 1 are readily seen by an operator and bear the same code numbers, figures or symbols 24 as the symbols on the cards.

The corresponding openings in said walls 2, 3, 16 are in horizontal alignment so that parallel

card sorting needles 25, 26 may be thrust through said openings. When this is done, the needles will be parallel with bars 13.

The needles 26 are the two end needles of the 5 row of needles, while needles 25 are those in the row between the needles 26. These needles 26 are preferably slightly longer than the needles 25.

The needles 25, 26 are each formed with a 10 spring loop 28 at the rear end, at the end that projects from the rear wall 3 of support 1 when the needles are in the desired aligned openings in walls 2, 3, 16. Each loop 28 has a spring arm extension 29 that projects forwardly of the upper side of each loop. The forward end of each extension 29 is formed with a downwardly slanting portion 30 that is adapted to extend over the upper edge of rear wall 3 and which portion 30 yieldably engages the said edge in a manner that tends to yieldably hold the needle from sliding 15 rearwardly.

Adjacent the above portion 30 the extension 29 terminates in an upwardly inclined portion 31. When the needles are inserted in the openings in said walls 2, 3, 16, the inclined portion 31 of each needle will ride up over the upper edge of wall 3 as the needle is finally pushed forward, and then the inclined portion 30 will ride down the said edge thus applying the resistance to withdrawal of the needles. However, by grasping with loop 28 and then forceably pulling the needles rearwardly, the spring extensions 29 will be released from wall 3.

The main straight, horizontal lengths of needles 25, 26 join the lower sides of the loops 35 28 by downwardly inclined portions 32 that commence at the openings in rear wall 3 through which the needles extend. These inclined portions function as stops for limiting the forward movement of the needles. In this manner inclined portions 30, 32 cooperate to hold the needles stationary and relative to the support unless forceably withdrawn for relocating in other aligned openings.

As seen in Fig. 3 the sides of openings in rear 45 wall 3 for needles 25, 26 may be outwardly flared at 35 where the openings open rearwardly outwardly of said wall to facilitate quick insertion of the needles in said openings. Also the pointed ends 36 of the needles facilitate such insertion. 50 As seen in Fig. 3 the needle will enter the opening as long as the point engages the flared sides 35 and even though the needle is not aligned with the openings.

In operation a horizontal row or stack of cards 55 37 may initially be in a sorting tray 38 with their marginally punched openings in alignment.

The spacer element 15 is slipped along bars 13 and the needles to the forward limit of the 60 spacer which is spaced from but adjacent the pointed ends of the needles. It will be seen that the spacer will function to correctly space the pointed ends of the needles when it is in the above position. Normally said pointed ends would not be correctly spaced inasmuch as the needles are light and are not exactly parallel.

When the spacer is in the above position, the operator may readily insert the end needles in the desired openings in the cards and the other needles will then automatically be correctly positioned for thrusting into the desired openings.

After the needles are thrust through the openings in the stack of cards, a supporting bar 40 is swung below the pointed ends of the needles 70 75 providing a support for the needles so that the

entire stack of cards may be lifted for releasing the desired card or cards 39 (Fig. 2).

Bar 40 has legs 41 at its ends that project at right angles from said bar. The outer ends of said legs are pivoted to the forward ends of parallel forward extensions 42 at the ends of strip 11.

The fact that the handle 10 extends forwardly between support 1 and the strip 11 makes it easy to lift a relatively heavy stack of cards. The supporting bar 40 prevents any detrimental strain to be placed on said needles or on the device as a whole.

The needles themselves are about the thickness of conventional steel knitting needles, hence are susceptible of being sprung out of position, if not supported. The structure described gives that support.

Changing the needles for sorting different cards is very simple since the operator need merely compare the desired coded and slotted card with the chart on rear wall 3 and then position the needles according to the slots.

I claim:

1. A card sorting device of the character described comprising a support having a horizontally extending row of openings therein adapted to support horizontally extended sorting needles therein at points respectively adjacent one of the ends of said needles, horizontally extending sorting needles removably supported at said points in certain of said openings as selected, the opposite ends of said needles being aligned horizontally and being pointed to facilitate their insertion into the aligned marginally punched openings formed in a stack of sorting cards, a spacer carried by said support adjacent the pointed ends of said needles in engagement with the latter for holding said pointed ends in proper spaced relationship during such insertion of said needles in said marginally punched openings, and means supporting said spacer for movement relative to said needles toward said support to permit movement of such stack along said needles, and a member positioned above and adjacent the pointed ends of said needles and secured to said support for movement to and from a position below said needles outwardly of said spacer relative to said support for supporting said needles when such cards are suspended therefrom and said spacer is between said cards and said supports.

2. A card sorting device of the character described comprising a support having a horizontally extending row of openings therein adapted to support horizontally extended sorting needles therein at points respectively adjacent one of the ends of said needles, horizontally extending sorting needles removably supported at said points in certain of said openings as selected, the opposite ends of said needles being aligned horizontally and being pointed to facilitate their insertion into the aligned marginally punched openings formed in a stack of sorting cards, a spacer carried by said support adjacent the pointed ends of said needles in engagement with the latter for holding said pointed ends in proper spaced relationship during such insertion of said needles in said marginally punched openings, and means supporting said spacer for movement relative to said needles toward said support to permit movement of such stack along said needles, and a member positioned above and adjacent the pointed ends of said needles and secured to said support for movement to and

from a position below said needles outwardly of said spacer relative to said support for supporting said needles when such cards are suspended therefrom and said spacer is between said cards and said support, and a handle spaced above said needles connecting said support to said member.

3. In a card sorting device of the character described comprising a horizontally elongated support having a horizontally extending row of coded openings formed therein adapted to support horizontally extending sorting needles therein at points respectively adjacent one of the ends of said needles, horizontally extending parallel sorting needles removably supported at said points in certain of said openings as selected, said needles being arranged in a horizontal row with the ends of the outermost needles of said row that are most remote from said support projecting farther from said support than the needles between them and said latter needles having their ends remote from said support in alignment longitudinally of said row for simultaneous insertion into the aligned marginally punched openings formed in a stack of sorting cards, a spacer parallel with said support formed with a row of openings corresponding in spacing with the openings in said support, each of said needles extending through the opening in said spacer that corresponds in position with the opening in the support in which it is held, and means connected with said support supporting said spacer for movement on said needles from their outer ends remote from said support toward the latter.

4. In a card sorting device of the character described comprising a horizontally elongated support having a horizontally extending row of coded openings formed therein adapted to support horizontally extending sorting needles therein at points respectively adjacent one of the ends of said needles, horizontally extending parallel sorting needles removably supported at said points in certain of said openings as selected, said needles being arranged in a horizontal row with the ends of the outermost needles of said row that are most remote from said support projecting farther from said support than the needles between them and said latter needles having their ends remote from said support in alignment longitudinally of said row for simultaneous insertion into the aligned marginally punched openings formed in a stack of sorting cards, a spacer parallel with said support formed with a row of openings corresponding in spacing with the openings in said support, each of said needles extending through the opening in said spacer that corresponds in position with the opening in the support in which it is held, and means connected with said support supporting said spacer for movement on said needles from their outer ends remote from said support toward the latter, a rod extending longitudinally of said row swingable for movement from a position below the ends of said needles remote from said support to a position elevated above the said needles, and means carried by said support swingably mounting said rod for so swinging.

5. In a card sorting device of the character described comprising a horizontally elongated support having a horizontally extending row of coded openings formed therein adapted to support horizontally extending sorting needles therein at points respectively adjacent one of the ends of said needles, horizontally extending parallel sorting needles removably supported at

said points in certain of said openings as selected, said needles being arranged in a horizontal row with the ends of the outermost needles of said row that are most remote from said support projecting farther from said support than the needles between them and said latter needles having their ends remote from said support in alignment longitudinally of said row for simultaneous insertion into the aligned marginally punched openings formed in a stack of sorting cards, a spacer parallel with said support formed with a row of openings corresponding in spacing with the openings in said support, each of said needles extending through the opening in said spacer that corresponds in position with the opening in the support in which it is held, and means connected with said support supporting said spacer for movement on said needles from their outer ends remote from said support toward the latter; a rod extending longitudinally of said row swingable for movement from a position below the ends of said needles remote from said support to a position elevated above the said needles, and means carried by said support swingably mounting said rod for so swinging, said means including a handle spaced above said needles and extending longitudinally thereof.

6. In a card sorting device of the character described comprising a horizontally elongated support having a horizontally extending row of coded openings formed therein adapted to support horizontally extending sorting needles therein at points respectively adjacent one of the ends of said needles, horizontally extending parallel sorting needles removably supported at said points in certain of said openings as selected, said needles being arranged in a horizontal row with its ends of the outermost needles of said row that are most remote from said support projecting farther from said support than the needles between them and said latter needles having their ends remote from said support in alignment longitudinally of said row for simultaneous insertion into the aligned marginally punched openings formed in a stack of sorting cards, a spacer parallel with said support formed with a row of openings corresponding in spacing with the openings in said support, each of said needles extending through the opening in said spacer that corresponds in position with the opening in the support in which it is held, and means connected with said support supporting said spacer for movement on said needles from their outer ends remote from said support toward the latter, means connecting said spacer with said support for holding said spacer parallel with said support during its movement toward and away from the latter; a rod extending longitudinally of said row swingable for movement from a position below the ends of said needles remote from said support to a position elevated above the said needles, and means carried by said support swingably mounting said rod for so swinging, said means including a handle spaced above said needles and extending longitudinally thereof.

7. In a card sorting device of the character described comprising a horizontally elongated support having a horizontally extending row of coded openings formed therein adapted to support horizontally extending sorting needles therein at points respectively adjacent one of the ends of said needles, horizontally extending parallel sorting needles removably supported at said points in certain of said openings as selected, said needles being arranged in a horizontal row with the ends of the outermost needles of said row that are most remote from said support projecting farther from said support than the needles between them and said latter needles having their ends remote from said

support in alignment longitudinally of said row for simultaneous insertion into the aligned marginally punched openings formed in a stack of sorting cards, a spacer parallel with said support formed with a row of openings corresponding in spacing with the openings in said support, each of said needles extending through the opening in said spacer that corresponds in position with the opening in the support in which it is held, and means connected with said support supporting said spacer for movement on said needles from their outer ends remote from said support toward the latter, means connecting said spacer with said support for holding said spacer parallel with said support during its movement toward and away from the latter, said means including a pair of bars parallel with said support connected at one of their ends to said support and positioned adjacent the opposite ends of said spacer respectively, pulley rollers on said spacer adjacent its ends, and a pair of cords each connected at one of its ends to the ends of said bars that are remote from said support and extending around both of said pulleys and secured at their opposite ends to said support.

8. A card sorting device of the character described comprising a horizontally elongated support formed with a row of spaced openings extending longitudinally thereof adapted to removably support horizontally extending sorting needles therein at points adjacent one of the ends of said needles, horizontally extending needles removably supported at said points in certain of said openings as selected, the ends of said needles opposite said points being pointed to facilitate their insertion into aligned marginally punched openings formed along the upper edges of vertically positioned sorting cards, said support including members rigid therewith and extending at right angles thereto in the same direction as said needles at a level above said row of needles and terminating adjacent to and short of the pointed ends of said needles whereby said pointed ends will be free for insertion into said punched openings, a spacer parallel with said support formed with openings corresponding with those formed in said support and through which said needles slidably extend, said spacer being slidably supported on said members for reciprocable movement from end to end thereof, a handle for lifting said support, members, spacer and needles including cards adapted to be held on the latter, said handle being secured to said support and extending over the spacer and over said row of needles and the cards adapted to be held on the latter, and means connecting the ends of said members that are remote from said support with the end of said handle that is nearest the pointed ends of said needles.

9. A card sorting device of the character described comprising a horizontally elongated support having a horizontally extending row of openings formed therein adapted to support a horizontal row of horizontally extending sorting needles therein at points adjacent one of the ends of said needles, horizontally extending sorting needles removably supported at said points in certain of said openings as selected and the opposite ends of said needles remote from said support being pointed to facilitate their insertion into the aligned marginally punched openings formed in vertical sorting cards along their upper edges, horizontally elong-

gated spacer parallel with said support and formed with a horizontal row of openings corresponding with those formed in said support and through said needles slidably extend, spacer supporting means rigid with said support above the level of said needles supporting said spacer for movement between said support and the outer ends of said needles and spacer holding means independent of said spacer supporting means connecting said spacer with said support for holding said spacer parallel with said support during its said movement irrespective of the position of the point along said spacer at which force is applied to move said spacer, said spacer holding means including rollers carried by said spacer adjacent its ends and cards secured at one of their ends to ends of said support and secured at their other ends to said spacer supporting means and extending around said

rollers intermediate their respective opposite ends.
